BEDSTEAD

Unice C. Sharp, 22 Annapolis St., Battle Creek, Mich.

Filed Jan. 6, 1965, Ser. No. 83,285

Term of patent 3½ years

(Cl. D5—4)

FIG. 1

The back face of the headboard is plain and unornamented.

I claim:

The ornamental design for a bedstead, substantially as shown and described.
